UNITED STATES PATENT OFFICE.

FRANCIS ADIX, OF BOONE, IOWA.

ENSILAGE-TAMPING DEVICE.

1,256,633.

Specification of Letters Patent. Patented Feb. 19, 1918.

Application filed July 13, 1916. Serial No. 109,197.

To all whom it may concern:

Be it known that I, FRANCIS ADIX, a citizen of the United States, and resident of Boone, in the county of Boone and State of Iowa, have invented a certain new and useful Ensilage-Tamping Device, of which the following is a specification.

My invention relates to devices for tamping and packing ensilage in silos.

10 The object of my invention is to provide an ensilage tamping device of simple construction and of comparatively low cost which will be efficient and durable.

15 A further object is to provide an ensilage tamper having a weight adapted to be reciprocated in such a way that the weight may be readily and easily moved to different positions in a silo.

20 A further object is to provide in connection with such a tamping device, as has just been described, operative mechanism for reciprocating the tamping weight, so constructed and arranged as to automatically take up the slack in the rope or other flexible device connected with the weight as the silo is filled.

25 It is a further object to provide such a mechanism so arranged as to automatically, alternately raise the weight by means of a rope or the like and then to release the rope and permit the weight to be dropped on the ensilage.

30 A further object is to provide in such a mechanism, means for operatively throwing the mechanism out of gear, said means being capable of being extended into the silo, so that it may be operated by persons within the silo.

35 My invention consists in the construction, arrangement and combination of the various parts of the device, whereby the objects contemplated are attained, as hereinafter more fully set forth, pointed out in my claim and illustrated in the accompanying drawings, 45 in which:

Figure 1 shows a side elevation of a silo, the upper portion being in vertical cross section, equipped with my improved ensilage tamping device, the operative mechanism 50 being shown in side elevation.

Fig. 2 shows a top or plan view of the silo wall with the cover removed, showing the arrangement of the frame work which supports the tamping device.

Fig. 3 shows a plan view of the operative mechanism.

Fig. 4 shows a detail, sectional view taken on the line 4—4 of Fig. 3.

Fig. 5 shows a detail, sectional view taken on the line 5—5 of Fig. 3, and

Fig. 6 shows a top or plan view of the tamping weight.

In the form of my invention illustrated in the accompanying drawings, I have used the reference numeral 10 to indicate generally an ordinary circular silo having a top or cover 11 provided with a projecting gable 12.

Secured to the upper portion of the top on the under surface thereof is a frame member 13. The members which are supported on the frame 13 may have different forms, but in the form of the invention shown herein, I use an upwardly opening U-shaped bracket 14 having its arms embracing on opposite sides of the members 13 and secured thereto.

Spaced below the bracket 14 is a similar bracket 15 having an inverted U-shape.

The shaft 16 is extended through the brackets 14 and 15. The lower bracket 15 is 80 rotatably mounted on said shaft.

Secured between the arms and brackets 15 and extending downwardly therefrom is an arm 17 the lower end of which is received between the arms of an upwardly opening U-shaped bracket 18, the arms of which are secured to the arm 17.

Mounted for rotation below the bracket 18 is a frame 19, shown in Figs. 1 and 2, comprising two spaced horizontal bars having 90 mounted therebetween two horizontal spaced guide rollers 20.

Mounted on the shaft 16 between the brackets 14 and 15 is the upper end of an arm 21, which is inclined from its upper end downwardly and outwardly and forms a brace for securing and supporting the outer end of an arm 22. The inner end of the arm 22 is suitably supported below the bracket 18, upon the shaft 23 which extends through the bracket 18 and the upper bar of frame 19.

At the outer end of the arm 22 are downwardly extending spaced arms 24 between which is rotatably mounted a pulley 25.

105 Mounted on the shaft 23 are a pair of arms 26 which extend divergently away from the shaft 23 and are adjustably se-

cured to arms 27 by means of bolts 28. The arms 27 are secured to the silo frame on opposite sides of the door opening therein and serve to brace the lower end of the 5 arm 17 and hold it properly centered in the silo.

It will be seen that the arm 22 can be swung around in the silo, and that it is limited in its directions of movement by 10 the respective arms 27 and 26.

My improved tamping weight preferably comprises three blocks 29, 30 and 31 secured together by means of bolts 32, side by side in a horizontal plane. The block 15 31 preferably has a curved outer surface at 33 designed to conform generally to the curvature of the silo wall, for permitting the block to approach close to the silo wall for tamping the ensilage adjacent to the 20 silo thoroughly.

Fixed to the central block 30 is a bolt 34 to which is fastened a rope 35 or other flexible device, which is extended upwardly over the pulley 36 and between the pulleys 25 20, and thence over a pulley 36 mounted on the frame of the silo at the upper part of the door opening and thence downwardly to the operating mechanism as hereinafter described.

30 Pivoted to the inner member 29 of the weight, is a handle 37, whereby the weight may be swung from one position to another for tamping ensilage in all parts of the interior of the silo.

35 I provide suitable mechanism for alternately raising the weight for a short distance and then releasing the rope 35 for letting the weight drop to tamp the contents of the silo, said operating mechanism comprising a frame having a horizontal, longitudinal member 38, and horizontal, traverse members 39 forming a frame which is suitably supported upon wheels 40, whereby there is constructed a truck 45 having a tongue 41 and the operating mechanism is mounted on the truck just described, and can be readily and easily moved from place to place. The truck can be anchored in any suitable way near the silo 50 when the machine is in use.

Suitably mounted on the frame of the truck, preferably transversely thereof is a shaft 42, on which is rotatably mounted a drum 43. At one end of the drum 43 55 is a suitable annular member 44 adapted to coat with the brake-shoe 45 mounted on a lever 46 preferably having the bell crank form. The lever 46 is pivoted between its ends, as shown in Fig. 5. The 60 spring 47, secured to the upper portion of the lever 46 and to the frame of the machine, normally tends to draw the lever 46 to position where brake-shoe 45 engages the coacting brake-shoe member 44 on the 65 drum 43.

Extending laterally from the upper end of the lever 46 is a roller 48.

On the drum 43 preferably opposite the end thereof having the brake member 44 is a ratchet 49.

70 Loosely mounted on the shaft 42 is a beveled gear 50 to which is pivoted a pawl 51 having an engaging member 52, adapted to coat with the teeth of the ratchet 49, and having a comparatively long outwardly extending arm or handle member 53. The pawl 51 also has an arm 54. A spring 55 secured to the arm 54 and to the beveled gear 50, yieldingly holds the engaging member 52 of the pawl 51 in engagement with the teeth of the ratchet 49.

75 Suitably mounted on the frame of the machine, is an engaging member 56 adapted to extend in the path of travel of the arm 53, whereby the pawl 51 will be moved out of engagement with the ratchet 49 at one time during each revolution of the beveled gear 50. It will be understood that the arm 53 is of such length that during the time it is engaged by the member 56, the drum 43 will be freed long enough for the weighted member to drop from its raised position to rest on the ensilage. Although the weight does not fall the same distance, on account of the filling of the silo with ensilage or because of irregularities in the upper surface of the ladder, the rope 35 will nevertheless be wound up on the drum a predetermined distance with each engagement of the pawl 52, whereby the rope will automatically adjust its length to the height of the weight in the silo.

80 Rotatably mounted on the frame of the truck is a shaft 57, preferably arranged longitudinally of the truck on substantially the same level as the shaft 42.

85 Rotatably mounted on one end of the shaft 57, is a sleeve 58 having on one end a beveled gear 59 in mesh with the beveled gear 50 and having at its other end a clutch 100 member 60.

90 Slidably but non-rotatably mounted on the shaft 57 is a coacting clutch member 61.

95 Centrally pivoted on a bracket 63, mounted on the frame of the truck, is a lever 64, one end of which is operatively connected with the clutch member 61, and the other end of which is secured to a spring 65 and also to a rope 66. The spring 65 is secured to the frame of the machine and is adapted to normally move the lever 64 to position for holding the clutch members 61 and 60 in engagement with each other.

100 The rope 66 extends over a guide pulley 67 mounted on the frame of the machine 125 on the opposite side of the lever 64, from the spring 65, in such position that when the rope 66 is pulled, the lever is moved against the tension of the spring 65 to position for disengaging the clutch members 130

The rope 66 extends over the pulley 67 upwardly over a guide pulley 68 at the upper part of the silo frame, and thence into the interior of the silo, so that said rope 5 66 is accessible to a person on the interior of the silo, for permitting such person to throw the clutch members out of engagement.

On the shaft 57 is a pulley 69 or other 10 suitable gearing device, whereby rotation may be imparted to the shaft 57 from any suitable source of power.

The rope 35 extends downwardly over the pulley 36 and is wound on the drum 43. 15 The lever 46 and the roller 48, are so located with relation to the drum 43 and the rope 35, that the rope 35 travels over the roller 48, as shown in Fig. 5, in such manner as to move the lever 46 to position 20 for releasing the brake-shoe 45 at all times, when the rope 35 is taut. When, however, the rope 35 is allowed to become slack, it will be obvious that the spring 47 will draw the brake 45 into engagement with the 25 acting brake member 44 on the drum 43.

In the practical operation and use of my improved ensilage tamping device, the frame for supporting the rope 35 and the pulleys 25 and 20 are installed at the top of the 30 silo. The rope 35 is threaded over the pulleys in the proper manner, and the truck with the operative mechanism thereon is moved to proper position with relation to the silo, and is suitably anchored.

The rope 35 is wound on the drum and 35 the rope 66 is extended over the pulley 68. The gearing device 69 is connected with the source of power which runs the ensilage cutter, or some other prime mover, and the 40 machine is ready for operation.

It may be well to mention at this point, one or two of the problems involved in the storage of ensilage. The ensilage is cut with a machine for that purpose and elevated to the upper part of the silo and discharged through a long flexible chute.

It is necessary that the ensilage be tamped or packed in the silo. This is ordinarily done by men who simply tramp it down 50 as it is fed in through the chute. This work requires the man to handle the chute, and another man or men to tramp the ensilage.

It is extremely difficult to get men to work 55 in a silo for the purpose of packing the ensilage. The work is very hard and it is obvious that during summer weather and warm autumn days air in the silo is very close and disagreeable.

60 It is consequently difficult to find men who will do this kind of work. Even if they can be found, the use of men for this purpose is expensive.

Where my improved device is used, one 65 man can handle the end of the chute and

discharge the ensilage where he desires, and can also, by means of handle 37, swing the tamping weight to any position desired in the silo for thoroughly packing the ensilage discharged from the chute.

70

On account of the manner in which the pulley 25 is supported on the arm 22, and the manner in which the arm 22 is supported for swinging around the center of the silo, the operator can readily swing the weight 75 to practically any part of the silo.

If, for any reason, any parts of the mechanism should not operate properly, the operator in the silo can by means of the rope 66, disengage the clutch and throw the tamping 80 mechanism out of gear.

The tamping mechanism will move into gear automatically whenever the tension on the rope is released.

One very important feature of my device 85 arises from the mounting of the rope 22 for swinging around the silo. It will be noted that its swinging movement is limited by the arms 26 and 27, so that the tamping weight 90 can be easily swung into the space between 95 and below said arms.

One of the important advantages of my improved machine, arises from the arrangement of the pawl and ratchet mechanism in combination with the brake. The size of the 95 gear 50 is such that the weight is drawn up approximately two feet and then dropped. When the handle on the pawl engages the device 56, a slight further rotation of the shaft 57 moves the pawl away from the 100 member 56 and permits it to again engage with the ratchet on account of the action of the spring 55.

The roller 48 and the parts connected therewith are so arranged that when the 105 rope 35 is taut, the roller is held up by said rope for holding the brake shoe 45 out of engagement with the brake member 44. It will be obvious that if no brake device were employed, the dropping of the weight and 110 the rapid unwinding of the rope 35, would rotate the drum with such momentum that more than two feet in length of the rope 35 would unwind therefrom. However, when the pawl is released and the weight in the 115 silo unwinds the rope 35, and said rope is permitted to be slack, or when no tension is imposed thereon, the spring 47 immediately moves the brake-shoe 45 into engagement with the brake member 44, so that only a 120 sufficient length of the rope is unwound to permit the weight to do its work.

It will thus be seen that the rope will be held practically taut at all times, although immediately after the pawl is released, not 125 enough tension will be imposed on the rope to hold the brake in inoperative position. It, therefore, follows that while the beveled gear 50 is of such size as to raise the weight practically two feet upon each upward 130

movement, it is not necessarily true that the weight drops the complete two feet.

As the silo fills up, the downward stroke of the rope will obviously be slightly less than the upward movement thereof and any slack in the rope will be automatically taken up. In other words, the length of the rope from the drum to the weight is automatically shortened as the silo fills up.

10. My entire device is of simple and inexpensive construction, and is so built that the parts secured to the silo may be readily removed therefrom and transferred on the truck which supports the operative mechanism from one location to another.

The weighted element is made in sections, so that its size and weight may be varied, as desired, and is provided with the curbed flat face, adapted to fit snugly on the interior of

the circular silo wall for thoroughly tamping the ensilage close to the wall.

I claim as my invention:

In an ensilage tamping device, an arm, means for supporting one end of said arm for permitting the arm to swing in a horizontal plane around said means, a brace connected with said means and connected with said arm for supporting the other end thereof, a guide device on the other end of said arm, guide devices on the first end of said arm adapted to swing therewith, a weight, a flexible device secured to said weight and extended around said guide devices, and means for operating said flexible device for alternately drawing said weight upwardly and then releasing said weight.

Des Moines, Iowa, June 26, 1916.

FRANCIS ADIX.
